Primary Examiner — Catherine R Oliver-Garcia(74) *Attorney, Agent, or Firm* — Banner & Witcoff, Ltd.(57) **CLAIM**

The ornamental design for a handle of a conducted electrical weapon, as shown and described.

DESCRIPTION

FIG. 1 is a bottom perspective view of a handle of a conducted electrical weapon showing our new design; FIG. 2 is a top perspective view thereof;

FIG. 3 is a front view thereof;

FIG. 4 is a rear view thereof;

FIG. 5 is a left side view thereof;

FIG. 6 is right side view thereof;

FIG. 7 is a top view thereof; and,

FIG. 8 is a bottom view thereof.

The broken lines within the shaded area represent features that form no part of the claimed design. The broken lines depicting the remainder of the handle of a conducted electrical weapon form no part of the claimed design.

1 Claim, 8 Drawing Sheets(56)
